UNITED STATES PATENT OFFICE.

WILLIAM TUTTLE, OF DOWAGIAC, MICHIGAN.

CHILL FOR CHILLING METAL.

SPECIFICATION forming part of Letters Patent No. 272,497, dated February 20, 1883.

Application filed October 16, 1882. (No model.)

To all whom it may concern:

Be it known that I, WILLIAM TUTTLE, of Dowagiac, county of Cass, and State of Michigan, have invented a certain Improvement in 5 Chills for Chilling Metals, of which the following is a specification.

My invention relates to that class of chills designed for chilling and forming holes through castings in the process of casting in molds.

10 The object of my present invention is to overcome the warping of the metal plates constituting the main portion of the chill, and also to provide the same with longitudinal recesses for retaining the sand filling, all of 15 which will be hereinafter described.

In order to aid others skilled in the art to which my invention relates to make and use the same, I will describe its features with reference to the drawings forming a part of this 20 specification, in which—

Figure 1 is an end view of the chill as it appears within the wheel-hub A when removed from the mold. Fig. 2 is an enlarged view of one of the thimbles D. Fig. 3 is a cross-sectional view of the chill and parts, having the thimble removed to show tapering ends f. Fig. 4 is an inside view of one of the metal plates B, showing longitudinal recesses C C. Fig. 5 is an elevated plan view of the chill, 30 having one of the thimbles D removed.

The chill consists of two metal plates, B B, of equal form and proportion, being flat on their joining faces and convexed on their exterior. Each end of the plates is shouldered 35 at a' with sloping ends f. The thimbles D are secured over the tapering ends, as shown in Figs. 1 and 5. Between the joining faces of the plates B B is a strip of wood, F. Any perishable material may be used, wood being 40 preferable, as it is cheap. The strip F is narrower than the metal plates, leaving channels on each edge, as shown in Fig. 3. I provide the plates B B with recesses C C, extending from shoulder a' to shoulder a', as shown in Fig. 45. When the plates are in position, as in Fig. 3, the channels form an opening having concave sides. The channels are filled with common core-sand. Placing the thimbles D in position, and filling the channels with sand, 50 the chills are baked to harden the sand filling and to expel moisture. The convexity of the recesses prevents the sand filling from falling

out of the channels while placing the chills in the molds for the purpose specified. The strip of wood, F, extends through the chill from shoulder to shoulder a' a', leaving an opening, C', between the tapering portions of the plates B B. (See Fig. 3.) The thimbles D are provided with a division or partition, a, passing through the diameter of the same, as shown in Figs. 2 and 5. When the thimbles are placed over the tapering portions of the plates B B, as in Fig. 5, the partition a passes within the opening C', as shown in Fig. 3. The thimbles, when forced over said ends, bind the metal plates to the wood or perishable center F, thus holding it in place. The thickness of the partition a should be less than that of the perishable center, to allow the partition a to enter the opening C' freely, and not to come 70 in contact with the metal plates B B, for the reason hereinafter described.

My present invention is designed as an improvement upon my Patent No. 265,646, dated October 10, 1882. In my former invention the 75 metal plates warp lengthwise in cooling, caused by the central portion burning away, forming a free passage for the air between the plates, cooling the flat sides, while the convexed portions are kept hot by the casting encircling 80 them. The cooling of the plates on their flat surfaces faster than on their convexed portions causes them to contract, drawing the end portions toward each other. The plates cool in this position, and when placed together, 85 the flat surfaces joining, they meet at the ends and are apart at the center, thus warping longitudinally. My present invention overcomes this difficulty. The partition a of the thimbles D being secured between the end portions of 90 the plates, prevents said portions from drawing toward each other in cooling, as heretofore described. The partition a being thinner than the perishable center F, it allows the plates to be slightly drawn toward each other, enough 95 to allow for shrinkage of the casting around the plates, the center having burned up, and also to free the circumjacent portion of the thimbles from the plates B B, which allows said thimbles to be removed, when the parts 100 B B may be drawn out of the casting.

Having described my invention in the most exact terms that I can give, what I claim as new, and desire to secure by Letters Patent, is—

1. In a metal-chill, the combination of the metal plates, flat on their inner faces, having longitudinal recesses O C in the same, said plates being convexed on their exterior, with 5 the perishable center piece, as and for the purposes set forth.

2. In a metal-chill, the combination of the metal plates B B, having longitudinal recesses

C C and a perishable center, the thimbles D D, having partitions a a, and sand filling, when arranged and combined for the purposes specified.

WILLIAM TUTTLE.
